UNITED STATES PATENT OFFICE

2,326,524

GOLF PRACTICING DEVICE

Claude White Davis, Roanoke, Va.

Application August 12, 1942, Serial No. 454,699

2 Claims. (Cl. 273—35)

This invention relates to new and useful improvements in golf practicing devices and more particularly to a device for practicing driving in a manner which will assure the person practicing that his practice is leading toward perfection.

Another important object of the invention is to provide a golf practicing device which will accurately guide students toward correct driving.

Another important object of the invention is to provide a golf practicing device which is of simple construction and of low cost to manufacture.

These and various other important objects and advantages of the invention will become apparent to the reader of the following description.

In the drawings:

Figure 1 represents a top plan view.

Figure 2 is a side elevational view.

Figure 3 is a section on the line 3—3 of Figure 1.

Figure 4 is an end elevational view of one of the boxes with a portion broken away showing one of the switches.

Figure 5 is a diagrammatic view showing the electrical connection between the electrical devices involved.

Figure 6 is a perspective view of the practice golf stick.

Referring to the drawings wherein like numerals refer to like parts, it can be seen that numeral 5 denotes a platform having a target spot 6, simulating a golf ball located at the forward edge thereof and equally spaced between the side edges of said platform 5.

The platform 5 rests upon a pair of end members of a frame which consists of said end members 7, 7 and side members 8, 8. The side members 8 project well forwardly of the forward edge of the platform and each has a super-frame consisting of an inclined frame portion 9 rising from the rear end of the corresponding frame member 8, disposed parallel as at 10 and then extending downwardly at the front of the apparatus to connect to the corresponding frame member 8, as at 11.

Within the confines of each of these side frame structures 8, 9, 10 and 11 (see Figure 2) is a substantially rectangular-shaped shed 12, open at its opposite side portions. A vane 13 is mounted swingably on a rod 14 within this shed and at the innermost side portion thereof, directly opposed to the platform 5. Each of these vanes 13 carries a spring contact 15 which is engageable with a fixed contact 16 when the vanes are swung to the broken line positions shown in Figure 4.

Suitably attached to one of the frame portions

11, as suggested in Figure 2, is a box 18 which may contain a suitable source of current, such as a pair of batteries 19 and upon this box 18 is mounted a lamp 21. This lamp is in a series circuit with the batteries 19 and switches, one of which is shown in Figure 4, so that it is necessary that both switches operate simultaneously before the lamp 21 will energize.

The person practicing will swing a club such as 10 is shown in Figure 6, and consists of a blade 23 attached to the end of a shaft 24, the blade being curved transversely and being slightly narrower at the end *a* than at the end *b*, due to the fact that when the club is swung there is a greater air deflection at the outer end of the blade than at the inner end and for this reason the blade at the outer end is somewhat constricted to equalize the air deflection at both ends.

It can be seen that when the club is swung over 20 the platform in an effort to drive the same directly over the golf ball simulating spot 6, the vanes 13 will respond to the resulting blast of air and swing in a direction to bring the contacts 15 thereon engaged with the contact 16 so that the series circuit A shown in Figure 5 will be completed in the clamp 21 energized.

However, if there is a slightest divergence in moving the club over the spot 6, both the vanes will not be operated uniformly, and one will not move as far as the other and will not make contact, thus the circuit A will not be completed.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A golf practicing device comprising a platform having a target spot thereon, a pair of open-sided sheds, one at each side of the target spot, a swingable vane in each of the said sheds, a switch operated by each of the vanes, an indicator device and a series including a source of current and said switches and device.

2. A golf practicing device comprising a platform having a target spot thereon, a pair of open-sided sheds, one at each side of the target spot, a swingable vane in each of the said sheds, a switch operated by each of the vanes, an indicator device and a series circuit including a source of current and said switches and device, and a practicing club comprising a shaft and a transversely arcuate-shaped blade at one end thereof.

CLAUDE WHITE DAVIS.
